UNITED STATES PATENT OFFICE.

JOHN L. CREVELING, OF NEW YORK, N. Y., ASSIGNOR TO SAFETY CAR HEATING AND LIGHTING COMPANY, A CORPORATION OF NEW JERSEY.

ELECTRIC REGULATION.

1,169,465.

Specification of Letters Patent. Patented Jan. 25, 1916.

Application filed December 29, 1910. Serial No. 599,872.

To all whom it may concern:

Be it known that I, JOHN L. CREVELING, a resident of the city, county, and State of New York, have invented certain new and useful Improvements in Electric Regulation, as set forth in the annexed specification and drawing forming a part thereof.

My invention pertains to that class of electric regulation wherein it is desired to automatically govern a generator in a predetermined manner.

As my invention is particularly applicable to those systems wherein a generator, driven at variable speed is used to charge a storage battery and operate lamps or other translating devices, it will be described with reference to such a system.

Figure 1 is a diagrammatic representation of one type of such system embodying the essentials of my invention. Fig. 2 is a modified form of system embodying the essentials of my invention.

In the drawing 1 represents a dynamo or generator provided with the usual field coil 2, having in series therewith a field controlling element 3, in this instance indicated as a rheostat of the carbon pile variety. From the dynamo 1, the positive lead 4 is carried to the positive side of the storage battery 5 and lamps or translating devices 6, both of which have their negative terminals carried to the negative lead 7 of the generator. The positive lead of the storage battery in Fig. 1 is shown as having in series therewith the solenoid 8 and the main lead 4 in Fig. 2 is shown as having the solenoid 9 in series therewith for a purpose which will hereinafter more plainly appear. Pivoted lever 10 controlling the element 3 is normally drawn in an upward direction as by adjustable spring 11 in such manner as to tend to decrease the resistance of the carbon pile 3 and increase the voltage of the generator. The lever 10 is provided at one extremity with the core of magnetic material 12 surrounded by the solenoid 13 which, when energized, tends to pull the core 12 downwardly and increase the resistance 3 to lower the voltage upon the generator.

50 In Fig. 1 the solenoid 13 is shown as having in series therewith a resistance 14 which may be either fixed or adjustable as desired

and the said coil 13 is placed in shunt across that portion of the system, the voltage upon which it is desired to use for the regulating factor of the generator. In this instance the said solenoid is shown as in shunt across the generator main circuit. 15 is a carbon pile or other suitable variable resistance in shunt around the resistance 14 in such manner as to be capable of varying the resistance in series with the coil 13. 16 is a pivotally supported lever normally drawn in a downward direction as by adjustable spring 17 against the adjustable contact 18. The lever 16 is provided at its end with a core, 19, of magnetic material, surrounded by the solenoid 8 in such manner that energization of the said solenoid tends to lift the core 19 against the action of spring 17 and compress the carbon pile 15 and reduce the resistance thereof in such manner as to increase the current in the coil 13.

In Fig. 2, the solenoid 13 is connected across that portion of the system with respect to which it is desired to govern the generator voltage and as shown, is connected across the main circuit and having in series therewith the variable resistance 20, indicated as of the carbon pile variety. The resistance 20 is varied in the same manner as the resistance 15 in Fig. 1, upon energization of the solenoid 9.

A practical operation of my improved system is substantially as follows:—In the system shown in Fig. 1 if the generator be running at such speed as to be capable of charging the storage battery and operating the lamps or translating devices, current will flow through the field 2 and the generator voltage may be regulated in a well known manner by proper variation of resistance 3. The current flowing through the lead 4 to the storage battery will pass through the solenoid 8 and tend to lift the same against the action of spring 17. Current will also flow through resistance 14 and solenoid 13 and tend to depress the lever 10 against the action of spring 11 in such manner as to increase the resistance 3 and lower the voltage of the generator. I so adjust the spring 11 that when the resistance 15 is very high, or of such dimensions as may

be chosen to have the same when the lever 16 is held against the stop 18, that any further increase in voltage across the circuit in shunt to which the solenoid 13 is placed, 5 will cause the same to draw the core 12 downwardly and prevent the generator voltage increasing above this point. I now so adjust the spring 17 that when the desired maximum current flowing to the storage battery through the coil 8 is reached, 10 any increase above this amount will raise the lever 16 in such manner as to decrease the resistance 15 and thus decrease the total resistance in series with the winding 13 and increase the strength thereof for a given voltage across the circuit to which it is placed in shunt and therefore the voltage which the coil 13 will tend to hold constant 15 across the circuit in shunt to which it is placed, will be varied in accordance with the current in the coil 8. In the system as shown in Fig. 2 I so adjust the spring 11 and the screw 18 that when the lever 16 is held upon the screw 18 and the desired voltage is reached across that portion of the circuit in shunt to which the coil 13 is placed, 20 any further increase in voltage will cause the core 12 to be drawn downwardly in such manner as to increase the resistance 3 and tend to prevent the generator voltage rising above that point. I now so adjust the spring 17 that when the maximum current desired, 25 as the output for the generator is reached, any increase in this current flowing in the solenoid 9 will raise the lever 16 so as to decrease the resistance 20 in series with the coil 13 and so strengthen the same that it will tend to hold the lower voltage constant 30 across that portion of the circuit to which it is placed in shunt.

From the foregoing, it will be obvious that I have produced means for regulating a generator, to hold its voltage constant throughout speed changes or other tendencies to cause variations in generator voltage and have provided means whereby the voltage to be held constant through these speed changes is modified in accordance with the current delivered in a circuit in the system.

I do not wish in any way to limit myself to the exact details of construction and operation above set forth as a mere diagrammatic representation of one form of employment of my invention, as wide departure may be made within the scope of said invention and as is set forth in the following claims:—

1. Means for regulating a generator comprehending a compressible regulating element; voltage responsive means for controlling the same; and means, including a compressible resistance, for varying the current in the said voltage responsive means depend-

ing upon current fluctuations beyond a predetermined value only.

2. Means for regulating a generator comprehending a regulating element; voltage responsive means for actuating the same; a compressible regulating element for affecting the current in said voltage responsive means; and means for controlling the same responsive to current fluctuations beyond a predetermined limit only.

3. Means for regulating a generator comprehending a regulator therefor, comprising compressible means and electro-responsive means tending to hold the generator voltage constant; combined with means for modifying the current in said regulating means depending upon the current beyond a predetermined value only flowing in a circuit supplied by said generator.

4. The combination with a generator and a supply circuit, of a regulator for the generator responsive to voltage fluctuations across the supply circuit, and a controller including a series coil for varying the action of the regulator by current above a predetermined limit supplied by said generator.

5. Means for regulating a generator comprehending a voltage regulator operable above a predetermined generator output, means for electrically varying the adjustment of said voltage regulator, and current operated means governing said last mentioned means and being inoperative below a certain predetermined current.

6. The combination with a source of variable electro-motive force and a circuit supplied thereby, of means for controlling said electro-motive force in response to voltage fluctuations, and means for adjusting the current in the voltage responsive means including a coil affected by current fluctuations in said circuit above a predetermined value only.

7. The combination with a source of electro-motive force tending to vary; voltage operated means for holding said electro-motive force substantially constant throughout tendencies to vary; and means affecting current responsive means for determining the value of electro-motive force to be held constant and affected only by current fluctuations beyond a predetermined value.

8. The combination with a generator driven at variable speeds; a coil and variable resistance for holding the voltage thereof substantially constant throughout speed changes; of resistance varying means for adjusting the standard voltage to be held constant at such values as to prevent the current supplied by the generator exceeding a predetermined limit.

9. The combination with a generator driven at variable speeds; a supply circuit; a coil operated variable resistance for regu-

lating the generator to hold the voltage across the supply circuit constant throughout speed changes; of a coil operated variable resistance for adjusting the voltage to be held constant across the supply circuit, whereby the current in said circuit, due to the voltage held constant, is prevented from

exceeding a predetermined value, and said adjusting means being inoperative when the current in said circuit is below this value.
